Primary Examiner — Bridget L Eland(74) *Attorney, Agent, or Firm* — Ware, Fressola, Maguire & Barber LLP(57) **CLAIM**

The ornamental design for a cable securing device for non-metallic electrical cable, as shown and described.

DESCRIPTION

FIG. 1 is a rear perspective view of a cable securing device for non-metallic electrical cable showing my new design.

FIG. 2 is a front perspective thereof.

FIG. 3 is a left side view thereof, the right side view being a mirror image thereof.

FIG. 4 is a top view thereof, the bottom view being a mirror image thereof.

FIG. 5 is a rear view thereof.

FIG. 6 is a front view thereof.

FIG. 7 is a cross-sectional view taken in the direction of line 7-7 in FIG. 4; and,

FIG. 8 is a cross-sectional view taken in the direction of line 8-8 in FIG. 3.

The broken line hatching shown in FIGS. 7 and 8 is included for the purpose of illustrating portions of the cable securing device for non-metallic electrical cable that forms no part of the claimed design.
